CLAIM

The ornamental design for a vehicle front deflector, as shown and described.

DESCRIPTION

FIG. 1 is a front and left perspective view of the vehicle front deflector according to the present disclosure;

FIG. 2 is a left end elevation view thereof, the right end elevation view being a mirror image;

FIG. 3 is a front elevation view thereof; and,

FIG. 4 is a bottom plan view thereof.

The broken lines shown in the drawings depict portions of the vehicle front deflector that form no part of the claimed design.
